(57) **CLAIM**

The ornamental design for an assembly, as shown and described.

DESCRIPTION

FIG. 1 is a front perspective view of an assembly showing our new design;

FIG. 2 is a front view thereof with an additional piece;

FIG. 3 is a back view thereof without the additional piece;

FIG. 4 is a side view of the assembly;

FIG. 5 is an opposite side view of the assembly;

FIG. 6 is a top view of the assembly;

FIG. 7 is a bottom view of the assembly; and,

FIG. 8 is an exploded view of the assembly.

The broken lines in the figures depict environment and portions of the assembly that form no part of the claimed design.
